ROTARY DUPLICATOR

Shinjiro Horii, Kanda-Ku, Tokyo, Japan

Application August 7, 1939, Serial No. 288,872

2 Claims. (Cl. 101—118)

This invention relates to a rotary duplicator for use in duplicating manuscript or typewritten documents, drawings and the like, employing a stencil.

5 One of the objects of this invention is to provide a rotary duplicator in which means is employed for preventing the press roller from being spoiled when there is fed no paper to be printed.

Another object of the invention is to provide a 10 simple and effective means for adjusting the head margin of the print.

In the accompanying drawings:

Figure 1 is a side elevation of a rotary duplicator according to this invention, with the cover removed to show the mechanisms;

Figure 2 is a front view showing in detail the paper feeler device;

Figure 3 is a detail of the mechanism for controlling the movement of the press roller;

20 Figures 4 and 5 are details showing two different positions of the mechanism operatively connected to the feeler device, and

Figures 6 and 7 are details showing two different 25 positions of the mechanism for varying the point of start of the movement of the press roller for the purpose of regulating the head margin of the print.

Referring to the drawings, upon a machine frame 1 there are mounted a printing drum 2 and 30 an inking drum 3, around which an endless silk screen 4 is passed as usual. 5 is an operating handle for rotating the drum 2 through gears 6 and 7. By operating said handle 5, rotation is also transmitted through gears 8, 9 and 10 to a driving 35 shaft 11 of a paper feeding device. Feeding elements 12 are operatively connected to said driving shaft 11 through a suitable link mechanism, so that the feeding elements 12 are adapted to be moved back and forth in contact with the uppermost 40 layer of the pile of papers. A press roller 13 is journalled in bearings which are mounted on the free ends of arms 15 fixed to a rod 14 which is rotatably mounted on the frame. The above-mentioned parts are of known construction, and 45 it will not require any further description.

At an outer extremity of said rod 14, there is 50 fixed another arm 15' carrying at its free end a pin 16. Fixed to the shaft 17 of the gear 9, there is a cam 18 which is adapted to engage with an antifriction roller 20 provided at the upper end of a vertical bar 19. It will be seen that as the gear 9 rotates the bar 19 is moved upwardly and downwardly controlled by the cam 18 engaging with the roller 20. Pivoted to the vertical bar 55 19 at 21 is a lifting lever 22 having a hooked por-

tion engaging with the pin 16 and serving to lift the press roller 13. The hooked portion of said lever 22 has two engaging portions, the first engaging portion 22' and the second engaging portion 22'', the former being normally in engagement with the pin 16 of the arm 15.

A paper feeler 23 is fixed to a horizontal feeler rod 24 which is journalled in the frame. Said rod 24 has fixed to one of its outer ends a controlling lever 25 which is adapted to engage with a projection 26 extending from the upper end of the lifting lever 22. As far as the printing paper A passes along the paper guide 27 as shown in Figure 4, the feeler arm 23 is held in light contact with the paper by gravity. On the contrary, if there is no paper passing along the paper guide 27, the free end of the feeler arm 23 will drop into a depression 28 formed in the paper guide 27, so that the controlling lever 25 will be oscillated to the substantially vertical position as shown in Figure 5. 20 In this position, the lifting lever 22 which is moving upwardly with the vertical bar 19 by rotation of the cam 18 will be oscillated counter-clockwise, because the projection 26 is caught by the lower end of the controlling lever 25. Consequently, the pin 16 on the arm 15' will be transferred from the first engaging portion 22' into the second engaging portion 22'' as shown in Figure 5. Thus, even at the end of the upward movement of the vertical bar 19 the lifting lever 22 will never move the 25 arm 15' for its full stroke, so that the press roller 13 will not come into contact with the printing drum 2.

By operating the handle 5, the paper feeding device will be actuated as well as the printing drum 2, thereby effecting automatic feed of the papers, so that so far as there is not any trouble in said feeding device a sheet of paper will always pass along the paper guide 27 almost continuously, so that the free end of the feeler 23 does not drop into the depression 28. Consequently, the controlling lever 25 is held in an inclined position as shown in Figure 4, so that the projection 26 on the lifting lever 22 will not be caught by the lower end of the controlling lever 25, but it will be moved upwardly in contact with the back of the controlling lever 25, turning the latter counter-clockwise, permitting the press roller 13 to move through its full stroke to come into pressing contact with the sheet of paper A against the printing drum 2, thereby completing the printing operation as shown in Figure 3.

As shown in Figure 1, an operating lever 29 is operatively connected to the lifting lever 22 by means of a bell crank 30 and a link 31. By said

operating lever 29, the lifting lever 22 may be manually actuated so as to have its hooked portion disengaged from the pin 16, so that the press roller 13 is always held in an inoperative position.

5 For the purpose of adjusting the head margin of the print, means is provided for varying the angular position of the high point (or starting point) of the cam 18 relative to the roller 20 on the vertical bar 19 by shifting said roller 20 to 10 the leading angular position which is in line with the line *a* or to the retarding angular position which is in line with line *b* as shown in Figures 3, 6 and 7. *c* is the neutral position.

32 is an adjusting wheel for effecting the margin 15 adjustment. Fixed to a stud 33 of said wheel 32 is an eccentric disc 34. A horizontal bar 35 has a projection 36 which is normally held in engagement with the periphery of the eccentric disc 34 by means of a spring 37. Pivoted at 38 to the 20 left end of the horizontal bar 35 is a three-armed lever 39 having a cam-like arm 40 and an actuating arm 41. Third arm of the lever 39 is normally pulled downwardly and held in engagement with the upper edge of the horizontal lever 35 by means 25 of a spring 42. The cam 18 has an antifriction roller 43 which is adapted to act upon the cam-like arm 40, and an antifriction roller 44 on the vertical bar 19 is adapted to be actuated by the actuating arm 41 of the three-armed lever 39 at 30 predetermined period of time during the cycle of rotation of the cam 18. The adjusting wheel 32 is provided with a reference mark 45 adapted to co-operate with another mark (not shown) provided on the frame for reading the rate of the 35 margin adjustment. A pivoted arm 46 is provided for engaging with a projection 47 on the vertical bar 19 when the latter swings to the right as shown in Figure 7, said arm 46 serving to prevent the return movement of said projection 47.

40 At the first part of the cycle of operation of the printing drum 2, the press roller 13 is held in its lowered position, so that the sheet of paper fed by the feeding elements 12 is not gripped by said drum 2 and the press roller 13. As the cam shaft 45 rotates, the cam 18 pushes the roller 20, lifting the vertical bar 19 and, consequently, the lifting lever 22 will lift the press roller 13 through the pin 16, arm 15', rod 14, arm 15, so that the printing is started by gripping the paper A between the drum 2 and the press roller 13 as shown in Figure 50 3. In this position, while the roller 44 is engaged by the actuating arm 41, it will be released from the arm 41 as the cam 18 rotates and the roller 43 thereon presses the cam-like arm 40 integral 55 with said actuating arm 41, so that the vertical bar 19 will tilt to the position of line *b* shown in Figure 7. When the roller 43 proceeds farther and releases the cam-like arm 40, as shown in Figure 6, the roller 20 on the vertical bar 19 will be out of the high point of the cam 18, so that the vertical bar 19 descends. It is to be understood that the roller 44 passes out of the path of the actuating arm 41 before the latter returns to its original position.

In Figure 3, when the adjusting wheel 32 is slightly rotated counter-clockwise, whereby the three-armed lever 39 is set shifted to the left, the roller 44 on the vertical bar 19 while moved upwardly will be pushed to the left by the actuating arm 41, so that the vertical bar 19 together with the roller 20 will assume the left inclined position *a* while being moved upwardly. In this case, said roller 20 is started to be lifted earlier than in the previous case, and greater head margin can be 10 obtained.

On the contrary, when the three-armed lever 39 is set shifted to the right, the roller 44 will not come into contact with the actuating arm 41, so that the vertical bar 19 will be lifted assuming 15 the rightwardly inclined position *b*. In this case, the roller 20 is started to be lifted later and a smaller head margin will be obtained.

What I claim is:

1. A rotary duplicator comprising a printing 20 drum, driving means for said printing drum, a press roller adapted to press the paper under printing against said printing drum, a paper feeding device actuated from said printing drum driving means, a rotating cam driven from said printing drum driving means, a vertical bar actuated by said rotating cam, a lifting lever pivoted to said vertical bar and having a hooked portion provided with the first and second engaging portions, a press roller lifting arm having a projection 25 and connected to bearings of said press roller, said projection being adapted to be engaged by said first and second engaging portions alternatively, and a paper feeler device having a depending controlling lever which is adapted to control the position of said lifting lever so as to place said lifting lever in such position that the said first engaging portion engages with the press roller lifting arm when there is a sheet of paper under 30 said feeler and in such position that the said second engaging portion engages with the press roller lifting arm when there is no paper under said feeler, so that the press roller lifting arm does not lift the press roller for its full stroke. 40

2. A rotary duplicator comprising a printing 45 drum, driving means for said printing drum, a press roller adapted to press the paper under printing against said printing drum, a paper feeding device actuated from said printing drum driving means, a rotating cam driven from said printing drum driving means; a vertical bar having an antifriction roller engaging with and actuated by said rotating cam, a lifting lever pivoted to said vertical bar and having a hooked portion engaging with a projection belonging to an arm 50 connected to bearings of said press roller, and means for varying the angular position of said antifriction roller on the vertical bar relative to said cam so as to vary the time of start of lifting the press roller with respect to the rotation of the 55 printing drum, whereby adjusting the head margin of the print. 60
